UNITED STATES PATENT OFFICE.

CHARLES H. VINAL, OF APPLETON, WISCONSIN.

CONCRETE-MIXER.

1,134,300.

Specification of Letters Patent. Patented Apr. 6, 1915.

Application filed June 13, 1914. Serial No. 344,939.

To all whom it may concern:

Be it known that I, CHARLES H. VINAL, a citizen of the United States, and resident of Appleton, in the county of Outagamie and

5 State of Wisconsin, have invented new and useful Improvements in Concrete-Mixers, of which the following is a description, reference being had to the accompanying drawings, which are a part of this specification.

10 This invention has for its object to provide a concrete mixer in which the receptacle for the raw materials is suspended and is capable of oscillation about an internal axis to cause the material to travel from one end 15 thereof to the other and become thoroughly mixed, and which is also capable of being suspended by one end so that the mixed material may be discharged through a suitable, valved opening at the other end.

20 Another object of the invention is to provide a concrete mixer in the form of a drum or receptacle for materials capable of resting on the ground and having an opening in its upper part through which the materials 25 may be introduced, said receptacle being adapted to be suspended by cables attached to both ends thereof so as to be elevated and carried horizontally from a place convenient for the introduction of the raw materials to the work where the mixed concrete 30 is to be deposited, the drum being subjected to an oscillating action from end to end by a pull on first one suspending cable and then on the other during its travel from one place 35 to the other so as to thoroughly mix the materials in transit, and then by the opening of the gate in the discharge spout end of the receptacle while the receptacle is suspended by means of the other end thereof 40 the mixing material may be directed into the building forms or other place of deposit.

With the above and other objects in view the invention consists in the concrete mixer as herein claimed and all equivalents.

45 Referring to the accompanying drawings in which like characters of reference indicate the same parts in the different views: Figure 1 is an elevation of a concrete mixer constructed in accordance with this invention, the inclined positions of the drum being shown in dotted lines; Fig. 2 is a side view of the drum resting on the ground with the suspending cables ready for attachment thereto; Fig. 3 is a view of the lower 50 end of the drum when suspended for dumping and showing the dumping gate thereof;

Fig. 4 is a similar view partly sectioned at right angles to the direction of the view in Fig. 3; and, Fig. 5 is an end view of the drum.

60 In these drawings 10 indicates the mixing drum which is preferably of sheet metal with an approximately cylindrical central portion and truncated conical end portions, one end being closed by a tight head and the 65 other end provided with a funnel-like spout 11 closed by a suitable gate which will be later explained. At the ends of the drum are supporting feet by which the drum may stand on the ground in a horizontal position 70 as shown in Fig. 2, the manner of forming the feet preferred for the purpose consisting of a strip of heavy band iron bent around and riveted to the ends of the drum with downwardly and outwardly projecting 75 loop portions at either side of the drum forming the feet 12. The central cylindrical portion of the drum is provided with a filling opening 13 through which materials for producing the concrete mixture are introduced, this opening being sufficiently large 80 to permit of the sand and stone being shoveled into the drum.

85 Connecting eyes 14 are mounted on the ends of the drum at the uppermost portion 90 of the metal bands forming the feet 12, and a pair of cables 15 and 16 which may be mounted in any suitable manner, as by passing over pulleys 17 on a horizontally swinging and sliding boom 18 of a derrick or 95 crane 19, having hooks 20 on their ends for engaging the connecting eyes 14 and these cables may be driven in any desirable manner as by hoisting drums, 15' and 16' respectively, so as to lift or lower both ends of 95 the drum together or independently.

The funnel-like discharge spout 11 terminates in a tubular mouth 21 across which is secured a bolt 22 having a pair of levers 23 pivotally mounted thereon. The bottom of 100 the mouth 21 is rounded to an arc shape with the bolt 22 as the center and angle iron arc-shaped guides 24 are secured to the side edges of the mouth to form guideways between their inturned flanges and the said 105 curved side edges of the mouth in which an arc-shaped sliding gate 25 travels. Ears 26 on the sliding gate 25 engage a bolt 27 connecting the lower ends of the pair of levers 23 and a bolt 28 connecting the upper ends 110 of said levers constitutes a handle by means of which the sliding gate 25 may be opened

or closed. A spring pressed bolt 29 is secured to the side of the drum and engages the handle 28 to lock the gate in its closed position.

5 In operation the drum is supplied with the raw material, sand, cement, crushed rock and water or whatever desired, while resting on the ground as shown in Fig. 2, the material being introduced through the opening 13, and the quantity thereof being considerably less than the capacity of the drum. The hooks 20 of the cables are then engaged in the connecting eyes 14 and the cables are drawn up so as to lift the drum and the 10 suspending means is moved to convey the drum to the desired location for the mixture. During the travel of the drum from the loading place to the dumping place one cable may be raised and lowered or both 15 cables may be moved in opposite directions so as to give the drum an oscillation about a central axis causing it to be tilted from one end to the other successively and thus producing an agitation of the contents as they 20 are thrown from one end of the drum to the other which will effect a complete mixture. On the arrival of the drum at the dumping place, which may be an open building form or other receptacle to receive the mixture, 25 the cable 15 is raised or the cable 16 lowered so as to suspend the drum with its spout end lowermost, the position shown in Figs. 3 and 4. The quantity of material supplied to the drum should not be sufficient to 30 overflow through the opening 13 in this position of the drum. By withdrawing the sliding bolt 29 the handle 28 may be grasped and thrown outwardly and downwardly to remove the sliding gate 25 from the mouth 35 21 of the spout and the concrete mixture will flow out of the drum through the spout and by means thereof it may be discharged exactly where it is desired. 40

By means of this invention there is no necessity for carting the material in wheelbarrows as with the stationary mixer, for the drum or drums may be charged whenever the material is stored. It is preferred to have several of the drums in use at the same time, one being conveyed and discharged while the others are being charged. Furthermore, the carting of the concrete mixture in wheelbarrows or other conveyers from the mixer to the place of deposit is avoided, the drum itself being conveyed directly from the place of storage of materials to the place of deposit and in the meantime

by its oscillating motions effecting the mixture of the materials, and when arriving at the place of deposit the mixture is spouted directly from the drum through the open mouth thereof. 60

It is to be noted that one or more of the mixing drums may be provided with a horizontal screen extending lengthwise therethrough between the feed opening 13 and the bottom of the drum and another discharge spout may be provided at the other end of the drum opening to the space above the screen so that sand or like granular material thrown into the drum through the opening 13 may be screened by the oscillations of the drum as in mixing, and the fine portions of the material passing through the screen may be discharged through the spout 11, while the coarse portions remaining above the screen may be discharged through the other spout. This enables the drum to be utilized for separating the fine sand from the coarse sand for surfacing.

The free flow of the materials from one end of the drum to the other may be interrupted by placing baffle plates, bars or rods inside of the drum so positioned as to cause the materials to become quickly and 85 thoroughly mixed.

The invention is not confined to the details of construction of the mechanical parts, as these may be varied without departing from the spirit and scope thereof, the essential feature of the invention being the operation of a concrete mixer by suspending and conveying the mixing drum from one place to another with an oscillating motion effecting the mixture. 90 95

What I claim as new and desire to secure by Letters Patent is:

1. A concrete mixer, comprising a drum, hoisting means at each end thereof, and separate means for operating each of the said hoisting means independently for giving the drum an oscillating motion that will tilt it from end to end. 100

2. A receptacle having a top and an end opening, the latter with a closure, and separate means for raising and lowering said receptacle, said means being connected respectively with the ends of said receptacle. 105

In testimony whereof, I affix my signature, in presence of two witnesses.

CHARLES H. VINAL.
